UNITED STATES PATENT OFFICE.

FRANK L. MARIMAN, OF PORTLAND, OREGON.

RAILWAY-SWITCH HEEL BLOCK.

Application filed April 14, 1928. Serial No. 270,034.

Heretofore, it has been customary to construct heel blocks for switches, with a solid or continuous web, the bolts being extended entirely through the block from the outside 5 of one rail to the outside of the other rail. As it is impracticable as a manufacturing proposition, to forge such solid blocks and drill the long bolt holes therethrough, such blocks are now formed of cast metal which 10 will not yield and consequently often results in breakage as well as bending and twisting of the bolts under traffic. Not only are the blocks themselves expensive, but more expense is necessary in replacing them and 15 traffic is often delayed, particularly where such a repair must be made within a switch-yard. Then too, the side of the block engaged by the switch rail, is prone to wear and such wear cannot be taken up with blocks 20 of the present day constructions.

It is the object of my invention to provide a heel block of new and improved, forged construction secured to the webs of the rails by independent sets of short bolts 25 which may be quickly and easily applied or removed and do not require the drilling of any long holes through the blocks, the bolts which fasten the switch rail to the block also serving as means for taking up wear on the 30 side of the block at which they are disposed. The block having this improved construction and relation with the rails, is free from the objections above enumerated. It possesses a sufficient degree of yieldability to 35 yield without breakage under ordinary traffic but even if broken, can be welded and built up easily in a few minutes at trifling expense. Then too, the short bolts do not become distorted as is the case with the 40 long bolts now used and they may be easily removed whenever necessary. The old blocks cause many derailments and wrecks because of rigidity and breakage, while in practice, the present invention reduces such 45 accidents as much as fifty percent. The railroad switch heel block has no relation with the railroad frog heel block, but is positioned at the heel of the switch points or tongues and away from and between the 50 frog and the switch points.

Fig. 1 of the accompanying drawings illustrates a top plan view of one side of a switch showing the improved heel block secured in position.

Fig. 2 is a transverse sectional view on 55 line 2—2 of Fig. 1.

Fig. 3 is an end elevation of the heel block.

Fig. 4 is a transverse sectional view there- 60 of.

Fig. 5 is a side elevation.

Fig. 6 is a top plan view.

Fig. 7 is a longitudinal sectional view on line 7—7 of Fig. 6.

In the drawings above briefly described, 65 a portion of a switch structure is shown embodying rails 8—9 disposed in converging relation, the rail 9 terminating in a switch tongue 10 whose switch point is denoted at 11. Interposed between the rail 8 70 and the rail 9—10—11 is the improved heel block 12.

The block is of forged construction, being of tapered, channel-shaped form and provided with end walls 13 integral with its longitudinal side walls 14 and its bottom 15. The bottom 15 is beveled to solidly rest upon the bases of the rails as seen in Fig. 2, the upper edges 16 of the side walls 14 are beveled to contact solidly with the lower sides of the 75 rail heads, and these side walls are of such dimensions as to leave spaces 17 between them and the vertical webs of the rails. Short bolts 18 secure one of the side walls 14 to the web of the rail 8, and other short bolts 19 secure 80 the other side wall to the webs of the rail 9—10—11. Wear will take place at the side of the block engaging the last-named rail, but this wear may be readily taken up by tightening the bolts 19, maintaining tight contact between the upper edge of the adjacent side wall 85 14 and the rail head, and between the bottom 15 and the rail base. When the side wall and the web have been drawn into contact with each other and consequently no more wear 90 can be taken up, the blocks at the right and left sides of the switch may be interchanged so that the previously unworn sides thereof will then be subjected to the wear, thereby 95 doubling the lives of the blocks.

Fish plates 20 are of course employed at the sides of the rails remote from the blocks 12.

To permit drainage of water from the channel of the block, one or more openings such as 105 21 may be provided therein.

For the reasons hereinbefore enumerated, the improved block is greatly advantageous

over those heretofore employed, and as probably the best results are obtainable from the exact details disclosed, they are preferably followed.

5 I claim:—

1. In a railway switch embodying two converging rails, one of which terminates in a switch tongue; an elongated one-piece longitudinally tapered heel block between said rails, said block being forged in longitudinally channeled form and provided with end walls rising from its bottom and connecting its side walls, said bottom of the block being beveled and resting solidly on the rail bases, 10 said side walls being spaced from the vertical webs of the rails and having beveled upper edges contacting with the lower sides of the rail heads, short bolts securing one of said 15

side walls to the web of one rail, and independent short bolts securing the other of said side walls to the web of the other rail. 20

2. A railway switch heel block of elongated one-piece longitudinally tapered form, said block being of forged construction, provided with a longitudinally channeled formation 25 and having end walls integral with and rising from its bottom, said end walls being integrally joined to the ends of the side walls of the block, said bottom being beveled to rest solidly on rail bases, said side walls having 30 beveled upper edges to contact with the lower sides of the rail heads.

In testimony whereof I have hereunto affixed my signature.

FRANK L. MARIMAN.
